UNITED STATES PATENT OFFICE.

FRANKLIN H. POWERS, OF WEST PALM BEACH, FLORIDA, ASSIGNOR OF ONE-FOURTH TO HARRY C. FUGATE, ONE-FOURTH TO LEWIS E. HEISLER, AND ONE-FOURTH TO RAYMOND C. KETCHAM, ALL OF WEST PALM BEACH, FLORIDA.

PROCESS AND APPARATUS FOR SEPARATING AND EXTRACTING THE FIBERS FROM FIBROUS MATERIALS.

1,359,101.

Specification of Letters Patent. Patented Nov. 16, 1920.

Application filed May 19, 1919. Serial No. 298,076.

To all whom it may concern:

Be it known that I, FRANKLIN H. POWERS, a citizen of the United States, residing at West Palm Beach, in the county of Palm Beach and State of Florida, have invented certain new and useful Improvements in Processes and Apparatus for Separating and Extracting the Fibers from Fibrous Materials, of which the following is a specification.

This invention relates to a process and apparatus for separating and extracting the fibers from fibrous growths or material, such as endogens, namely coconut stems, palm, metto, pineapple, and the like and an object of the invention is to provide a machine for this purpose wherein the fibrous material will be alternately subjected to crushing action of vertical and horizontal rolls for crushing the fibrous material and squeezing the juices therefrom and also partially effect the separation of the fibers, and further to provide jets of suitable cleansing fluid such as water or the like, which jets engage about the fibrous material from opposite directions during its passage from one set of rolls to the rolls in the set next thereto for cleaning the fibers of acid, pulp and foreign matter, and also lubricating or softening the fibers, preventing the cutting action of fiber upon fiber or roll on fiber in the succeeding roll, and further attaining such bleaching of the fiber as is obtained by the action of the cleansing fluid or water.

Another object of the invention is to provide in a machine as specified, a plurality of sets of vertical and horizontal drying rolls having yieldable surfaces between which the fiber passes after leaving the crushing and separating rolls, from which drying rolls the fiber emerges in a clean, dry and separated state.

A further object of the invention is to provide adjustable yieldable mounting for certain of said rolls to protect the fibrous material from jam and injury, and also to provide suitable pans or containers for receiving the by-products, such as the juices which are squeezed from the material during the passing between the rolls and washed therefrom by the jets of the cleansing fluids, to permit use of such by-products.

Other objects of the invention will ap-

pear from the following detailed description taken in connection with the accompanying drawings, forming a part of this specification, and in which drawings:

Figure 1 is a side elevation, showing parts in section, of the machine for separating and extracting the fibers from fibrous ma- 60

terials.

Fig. 2 is a top plan of the machine having parts in section.

Fig. 3 is a cross-section on the line 3—3 of Fig. 1, and

Fig. 4 is a cross-section taken on the line 4—4 of Fig. 1.

Referring more particularly to the drawings, wherein like characters indicate like and corresponding parts throughout the several views, 10 indicates the supporting platform of the machine which has upstanding sides 11 and 12 attached thereto and to which upper sides the top 13 of the frame of the machine is connected. The upstanding sides 11 and 12 are thickened at spaced points intermediate their ends and are provided with bearing openings forming bearings or journals for a plurality of horizontally positioned shafts 14, while the said thickened portions 15 of the sides are further provided at spaced distances from the bearing openings which form journals for the shafts 14 with elongated substantially oval-shaped openings 16 which receive therein bearing collars 17 in which the ends of the shafts 18 are journaled. The shafts 18 are positioned directly above the shafts 14 and their axes are parallel as clearly shown in the drawings. The side portions 11 and 12 are provided with vertically extending openings 19 therein, in the lower ends of which are seated spiral springs 20. The springs 20 engage against the bearings 17 and against plates or disks 21 which are mounted in the vertical openings 19 and against which disks the inner ends of bolts 22 abut. The bolts 22 are threadably connected as shown at 23 to the housing to permit their adjustment to regulate the tension of the springs 20.

Rollers 24 and 25 are mounted upon the shafts 14 and 18 respectively and the adjacent portions of these rollers are slightly spaced as clearly shown in Figs. 1 and 3 of the drawings to permit the passing between 105 the rollers of the fibrous material.

Positioned directly in back of each set of the horizontal rolls 24 and 25 is a set or pair of vertical rolls 26 and 27 which are substantially equal in diameter to the rolls 24 and 25 and which have their adjacent portions a distance substantially equal to the distance between the adjacent portion of the rolls 24 and 25 to permit of the passing between the rolls of each vertical set of the 10 fibrous material.

The rolls 24 and 25 may be plain steel pulleys with smooth surfaces or otherwise, and may be made from any suitable material other than steel, such as wood, cement, rubber, iron or other material or combinations thereof. If steel rollers are used it may be necessary to coat the same with bronze so that the acid from the fiber material will not affect the surfaces as much as the exposed steel rollers.

The rolls 26 are mounted upon shafts 28, which are journaled in suitable upper and lower bearings 29 and 30. The bearings 30 are seated in recesses 31 formed in the upper 25 surface of the bottom of support 10 of the supporting structure of the machine, and are held in proper position and in such manner as to permit limited movement thereof by spiral springs 32, the inner ends of which engage against the bearing blocks 30 while the outer ends are engaged by bolts or set screws 33 threadably carried by the supporting base 10 for adjustment to permit the regulating of the tension of the springs 32. The upper bearings 29 of the shafts 28 are slidably positioned in elongated openings 34 formed in the top or upper portions 13 of the supporting structure of the machine and they have flanges 35 formed upon their ends to 30 prevent moving of the bearing members laterally through the elongated openings 34. Spiral springs 36 engage against the bearings 29 and have their outer ends in turn engaged by bolts 37 which are adjustably carried by the supporting ring of the machine to permit their adjustment to regulate the tension of the springs 36 and consequently regulate the amount of pressure which is necessary to allow the rollers 26 to 40 yield on its bearing or to move from the rolls 27 of each set.

The rolls 27 of the sets of vertical rolls are mounted upon suitable carrying shafts 38, the lower ends of which are journaled in thrust bearings 39 carried by the supporting base 10, while the upper ends of the shafts are journaled in bearings 40 carried by the top or upper portion 13 of the supporting structure.

60 The horizontal shafts 14 and 18 are extended through the side portion 12 of the supporting frame of the machine and have gears 41 and 42 respectively mounted thereon. These gears, of each set of the horizontal shafts mesh with gears 43 and 44 of

slightly greater diameter than the gears 41 and 42. The gears 43 and 44 are carried by stub shafts 45 and 46 respectively, and thus power is transmitted from one set of the horizontal rollers in the machine to the next 70 set of horizontal rollers. The shafts 28 and 38, upon which the rolls 26 and 27 are mounted project upwardly through their upper bearings 29 and 40 and have gears 47 and 48 mounted upon their upper ends. The 75 gears 47 and 48 of each set of the vertical rolls mesh with gears 49 and 50 which are carried by stub-shafts 51 and 52 respectively, thus the rotary movement of one set of the vertical rolls is transmitted to the 80 next set of vertical rolls and so on throughout the entire machine.

Cleansing liquid supply pipes 52 and 53 are carried by the supporting structure of the machine, one above and the other below 85 the set of vertical rollers or rolls, and transversely extending nozzles 54 are connected to these supply pipes at spaced points, the said nozzle being positioned between the rolls 26 and 27 of each set of vertical rolls 90 outwardly of the nearest portion of these rolls as clearly shown in Fig. 1 of the drawings. The nozzles terminate short distances upon each side of the horizontal center of the machine so that the fibrous material 95 while passing from one set of horizontal rollers to the set of vertical rollers next thereto or from between the vertical rolls to the set of horizontal rolls next thereto will be subjected to crossed jets of water or 100 analogous cleansing fluid for freeing the fibrous material of juices, acids, pulps and other foreign material, as well as for assisting in the disintegration of the fibrous material and the separation of the fiber thereof. 105

A pan or trough 55 is positioned beneath the rolls of the machine and also beneath the lower supply pipe 53 for receiving the cleansing fluid, and the juices which are squeezed from the fibrous material by the 110 crushing and separating rolls. An outlet pipe 56 has communication with the outer end of the trough 55 and is adapted to carry off the juices or by-products to permit them to be used commercially if desired.

The supply pipes 52 and 53 and consequently the sets of nozzles 54 terminate forwardly of the rear or outlet end of the machine, and the rolls of the vertical and horizontal sets rearwardly of the terminals of 120 the supply pipes and nozzles have coverings or coatings 60 of yieldable material such as rubber, cork or the like upon their fiber engaging surfaces, the said rolls being adapted to squeeze the water from the fibers, 125 causing the fibers to emerge at the outlet end of the machine in a dry, clean and separated state.

A drive pulley 61 is positioned at or adjacent to the delivery end of the machine, it 130

being mounted upon a suitable shaft 62. A gear 63 is mounted upon the shaft 62 and it meshes with the uppermost gear 46 of the rearmost set of gears. The shaft 62 has a 5 bevel 64 mounted thereon which meshes with a bevel gear 65 mounted upon a vertical stub shaft 66 which is carried by the top 18 of the supporting structure of the machine. The stub shaft 66 has a gear 67 10 mounted thereon which meshes with the gear 48 of the rearmost set of gears 47 and 48 as clearly shown in Fig. 2 of the drawings.

The fibrous growths or material enter the 15 machine, first having pressure applied thereto against opposite sides for flattening it by the first pair of horizontal rollers 24 and 25 and upon emerging from between these rollers the crushed material is subjected to cross streams or jets of water or 20 analogous cleansing fluid issuing from the first set of nozzles 54 and the material then passes between the first set of vertical rolls 26 and 27, where pressure is applied at other 25 opposite sides, namely at right angles to the pressure which is applied by the horizontal rolls. Upon issuing from between the first set of vertical rolls, the thus crushed material is then subjected to the action of crossed 30 jets of cleansing fluid and then passes between a second set of horizontal rolls, this operation being continued until the fibrous material has passed between all of the sets 35 of vertical and horizontal rollers associated which are the nozzles 54 and after the fibrous materials have passed through these sets of rollers it will have the fiber thereof separated and extracted, the pulp, juices and foreign matter having been washed 40 away by the jets of water and deposited in the trough 55. After leaving the crushing and separating rolls, the fiber is then passed through the alternate horizontal and vertical sets of drying rolls, which have yieldable 45 or pliable outer surfaces 60 which squeezes the water from the fiber causing it to emerge at the outlet end of the machine in a thoroughly clean, dry and separated state. The yieldable mounting of the bearings 50 of one roller of each of the vertical and horizontal sets permit limited yieldable movement of these rollers to prevent the jamming and consequent fracturing of the fibers of the fibrous material.

55 Changes in details may be made without departing from the spirit of this invention, but;

I claim:

1. That process of separating and extracting the fibers from fibrous material which 60 consists in alternately bringing pressure on opposite sides of the fibrous material and subjecting the crushed material to jets of cleansing fluid with the pressure being

brought at different opposite sides during 65 the process.

2. That process of separating and extracting the fibers from fibrous material which consists in first bringing pressure upon fibrous material at opposite sides of the mass, 70 subjecting the fibrous material to action of a jet of cleansing fluid and subsequently bringing pressure upon other opposite sides of the mass.

3. That process of separating and extracting the fibers from fibrous material which consists in first bringing pressure upon the fibrous material at opposite sides of the mass, subjecting the fibrous material to action of crossed jets of cleansing fluid and 80 subsequently bringing pressure upon other opposite sides of the mass.

4. That process of separating and extracting the fibers from fibrous material which consists in first bringing pressure upon the 85 fibrous material at opposite sides of the mass, subjecting the fibrous material to action of a jet of cleansing fluid, bringing pressure upon other opposite sides of the mass, and again subjecting the fibrous material to the action of the jet of cleansing fluid.

5. Those steps in process of separating and extracting the fibers from fibrous material which consists in first bringing pressure upon the fibrous material at opposite sides of the mass, bringing pressure upon other opposite sides of the mass, and subsequently bringing pressure upon opposite sides of the mass upon which the pressure 100 was originally applied.

6. Those steps in process of separating and extracting the fibers from fibrous material which consists in first bringing pressure upon the fibrous material at opposite 105 sides of the mass, bringing pressure upon other opposite sides of the mass, subsequently bringing pressure upon opposite sides of the mass upon which the pressure was originally applied, and subsequently 110 applying pressure to the mass to dry the same.

7. That process of separating and extracting the fibers from fibrous materials which consists in first bringing pressure upon the 115 fibrous material at opposite sides of the mass, subjecting the fibrous materials to action of crossed jets of cleansing fluid, bringing pressure upon other opposite sides of the mass, and subsequently applying pressure to the mass to dry the same.

8. That process of separating and extracting the fibers from fibrous materials which consists in first bringing pressure upon the fibrous material at opposite sides of the 125 mass, subjecting the fibrous materials to action of a jet of cleansing fluid, bringing pressure upon other opposite sides of the

mass, again subjecting the fibrous material to action of a jet of cleansing fluid, and subsequently applying pressure to the mass to dry the same.

5 9. That process of separating and extracting the fibers from fibrous material which consists in first bringing pressure upon the fibrous material at opposite sides of the mass, subjecting the fibrous material to action of the crossed jets of cleansing fluid, bringing pressure upon other opposite sides of the mass, again subjecting the mass to action of crossed jets of cleansing fluid, and subsequently applying pressure to the mass 70 to dry the same.

10 10. In an apparatus for separating and extracting the fibers from fibrous material, the combination, in a unitary structure, of a plurality of sets of vertical and horizontal 75 crushing and separating rolls having smooth 80 surfaces.

11 11. In an apparatus for separating and extracting the fibers from fibrous material, the combination, in a unitary structure, of a 85 plurality of sets of vertical and horizontal crushing and separating rolls, and adjustable 90 yieldable bearings for one roll of each set.

12 12. In an apparatus for separating and 95 extracting fibers from fibrous material, the combination, in a unitary structure, of a plurality of sets of vertical and horizontal crushing and separating rolls, fluid supply 100 pipes, and nozzles branching off from said supply pipes for directing jets of cleansing 105 fluid against the fibrous material during movement from one set of rolls to the set next thereto.

13 13. In an apparatus for separating and 110 extracting the fibers from fibrous material, the combination, in a unitary structure, of a plurality of sets of vertical and horizontal crushing and separating rolls, liquid supply 115 pipes above and below said vertical rolls, and nozzles branching from said supply pipes for directing jets of cleansing fluid from opposite directions against the fibrous material during passage thereof from one set of rolls to the set next thereto.

14 14. In an apparatus for separating and extracting the fibers from fibrous material, the combination, in a unitary structure, of a plurality of sets of horizontal crushing and separating rollers, a plurality of sets 120 of vertical crushing and separating rollers, oppositely disposed nozzles for directing jets of fluid from opposite directions against the fibrous material during passage thereof from one set of rolls to the set next thereto, and supply pipes for supplying fluid to said nozzles.

15 15. In an apparatus for separating and extracting the fibers from fibrous material, the combination, in a unitary structure, of a plurality of sets of horizontal crushing 125

and separating rollers, a plurality of sets of vertical crushing and separating rollers, oppositely disposed nozzles for directing jets of fluid from opposite directions against the fibrous material during passage thereof from one set of rolls to the set next thereto, supply pipes for supplying fluid to said nozzle, and adjustable, yieldable bearings for one roll of each set. 70

16. In an apparatus for separating and extracting fibers from fibrous material, the combination, in a unitary structure, of a plurality of sets of crushing and separating rolls, the rolls in one set being disposed at angles to the rolls in the set next thereto. 80

17. In an apparatus for separating and extracting fibers from fibrous material, the combination, in a unitary structure, of a plurality of sets of crushing and separating rolls, the rolls in one set being disposed at angles with respect to the rolls in the set next thereto, oppositely disposed nozzles arranged for directing jets of fluid from opposite directions against fibrous materials during passage thereof from one set of rolls 90 to the set next thereto, and supply pipes for supplying fluid to said nozzles. 95

18. In an apparatus for separating and extracting fibers from fibrous material, the combination, in a unitary structure, of a plurality of sets of crushing and separating rolls, the rolls in one set being disposed at angles with respect to the rolls in the set next thereto, oppositely disposed nozzles arranged for directing jets of fluid from opposite directions against fibrous materials during passage thereof from one set of rolls to the set next thereto, supply pipes for supplying fluid to said nozzles, and a pan positioned beneath said rolls for receiving the juices squeezed from the fibrous material. 100

19. In an apparatus for separating and extracting fibers from fibrous material, the combination, in a unitary structure, of a plurality of sets of crushing and separating 110 rolls, the rolls in one set being disposed at angles with respect to the rolls in the set next thereto, oppositely disposed nozzles arranged for directing jets of fluid from opposite directions against fibrous materials 115 during passage thereof from one set of rolls to the set next thereto, supply pipes for supplying fluid to said nozzles, a pan positioned beneath said rolls for receiving the juices squeezed from the fibrous material, 120 and adjustable yieldable bearings for one roll of each set.

20. In an apparatus for separating and extracting the fibers from fibrous material, the combination, in a unitary structure, of a plurality of sets of crushing and separating rolls, the rolls in one set being disposed in angular relation to the rolls in the set next thereto, said rolls having smooth material engaging surfaces. 125 130

21. In an apparatus for separating and extracting the fibers from fibrous material, the combination, in a unitary structure, of a plurality of sets of crushing and separating rolls, the rolls in one set being disposed in angular relation to the rolls in the set next thereto, means for supporting said rolls, means for rotating the rolls, liquid supply pipes carried by said supporting means, and nozzles carried by said supply pipes for directing crossed jets of cleansing fluid against the fibrous material, during passage thereof from one set of rolls to the set next thereto.
- 5 22. In an apparatus for separating and extracting the fibers from fibrous material,
- the combination, in a unitary structure, of a plurality of sets of crushing and separating rolls, the rolls in one set being positioned in an angular relation to the rolls in the set next thereto, and a plurality of drying rolls having yieldable fibrous material engaging surfaces.
- 10 23. In an apparatus for separating and extracting the fibers from fibrous material, the combination, in a unitary structure, of a plurality of drying rolls arranged in sets, the rolls in one set being disposed angularly with respect to the drying rolls of the set next thereto, said drying rolls having yieldable fiber engaging surfaces.
